W. E. SCHWARZMANN,
STARTING MAGNETO,
APPLICATION FILED SEPT. 27, 1918.

1,412,972.

Patented Apr. 18, 1922.

By this Attorney Wolfgang E. Schwarzmann
Leon A. Rosenthal

UNITED STATES PATENT OFFICE.

WOLFGANG ERNEST SCHWARZMANN, OF SPRINGFIELD, MASSACHUSETTS, ASSIGNEE,
BY MESNE ASSIGNMENTS, TO AMERICAN BOSCH MAGNETO CORPORATION, OF NEW
YORK, N. Y., A CORPORATION OF NEW YORK.

STARTING MAGNETO.

1,412,972.

Specification of Letters Patent. Patented Apr. 18, 1922.

Application filed September 27, 1918. Serial No. 255,990.

To all whom it may concern:

Be it known that I, WOLFGANG E. SCHWARZMANN, a citizen of the United States, residing at 51 Bellclaire Avenue, Long Meadow, 5 Springfield, in the county of Hampden, State of Massachusetts, have invented certain new and useful Improvements in Starting Magneton; and I do hereby declare the following to be a full, clear, and exact description of 10 the invention, such as will enable others skilled in the art to which it appertains to make and use the same.

The present invention relates to starting magnetos, particularly to those of the hand driven type, and the primary object of the 15 invention is to provide a starting magneto having driving means of simple, rigid and durable construction, compactly and accessibly arranged in a manner nicely associated 20 with the magneto to produce a dust-tight device.

It is now usual to provide a starting magneto with the service magneto of an airplane, to work in conjunction with the distributor 25 of the service magneto to produce ignition sparks at will when the engine is at rest. The starting magneto should be light so as to subtract as little as possible from the lifting power of the airplane, and, at the same time, 30 it should be strong and durable to withstand the continued vibration and shock to which the airplane is subjected in flight.

In accordance with my invention, the objects are attained in a magneto which, as 35 heretofore, is devoid of a distributor but has driving means housed in a gear box carrying a bearing for the rotor or armature of the magneto and containing gearing of a high speed-increasing ratio for driving the rotor, 40 as by means of a handle exterior of the gear box. Preferably, the gearing consists of a gear fast on a shaft supported by bearings in two separable members of the gear box, and a pinion mounted in the gear box on the end 45 of the rotor or armature shaft in engagement with the gear. Also the gear box closes the driving end of the magneto, and the member of the gear box adjacent the magneto has a cup-shaped portion enclosing the slip ring 50 of the magneto, the bearing for the gear shaft carried by that member being closed to the interior of the magneto.

In the accompanying drawings illustrating this preferred embodiment of my in-

vention in application, as an example, to a 55 hand driven starting magneto of the bipolar type, Fig. 1 is a central vertical section through the magneto and gearing; Fig. 2 is a view of the driving end of the magneto, partly broken away and partly in section; 60 Fig. 3 is a section on line 3—3 of Fig. 1.

The magneto proper comprises the field magnet 1, the rotatable armature 2 having primary and secondary windings, the mechanical interrupter 3 connected in the circuit of the primary winding, and the slip ring 4 connected to the insulated terminal of the secondary winding. The armature rotates in end bearings, one of which is shown at 5, and the other of which is carried by the 65 end plate 6 forming a closure for the rear end of the magneto. The collector brush 7 engages the slip ring and conducts the ignition currents to the wire 8 which is connected to the starting terminal of the distributor of the service magneto driven by the 70 engine to be started by the operation of the starting magneto, as will be readily understood by those skilled in the art.

The gear box comprises two separable 80 members 9 and 10 housing the gearing and closing the driving end of the magneto. The gear 11 is fast with the shaft 12, and the pinion 13 is fast on the end of the armature shaft 14 in engagement with the gear to form 85 a speed-increasing gearing with a ratio of about 4 : 1. The member 9 carries a bearing 15 closed to the interior of the magneto to prevent the entry of lubricant and dust thereinto, and the member 10 carries the 90 bearing 16 through and beyond which the shaft 12 extends for connection of a suitable driving handle 17. The two members of the gear box are fastened together, with the 95 gearing therein, by means of the screws 18, and are fastened to the magneto proper by the screws 19.

The gear box member 9 has a cup-shaped portion at 20 enclosing and protecting the slip ring, and also it carries the bearing 5 for 100 the armature.

Having thus described my invention what I claim is:—

1. The combination of a starting magneto having a rotor, a driving gearing for said rotor, means for operating said gearing, and a housing for said gearing, said housing having bearings for said gearing and rotor and 105

having an extension around an end of said rotor.

2. The combination of a starting magneto having a rotor, driving gearing for said rotor, means for operating said gearing, and a housing for said gearing, said housing comprising separable sections having bearings for said gearing and said rotor, one of said sections having an extension around an 10 end of said rotor.

3. The combination of a starting magneto having a rotor, driving gearing for said rotor, means for operating said gearing, and a housing for said gearing, said housing 15 being separable from said magneto and having bearings for said gearing and rotor, and having an extension around an end of said rotor.

4. The combination of a starting magneto 20 having a rotor, driving gearing for said rotor, means for operating said gearing, and a housing for said gearing, said housing having bearings for said gearing and rotor and having a cupped-shape extension 25 around the end of said rotor.

5. The combination with a starting magneto having an armature with a slip ring; of driving gearing therefor comprising a separable gear box closing the driving end 30 of the magneto, a gear mounted for rotation in the gear box, means for rotating the gear, and a pinion mounted in the gear box on the end of the armature in engagement to the

gear, the gear box member adjacent the magneto having a cup-shaped portion enclosing 35 the slip ring, and a bearing supporting one end of the armature.

6. The combination with a starting magneto having an armature with a slip ring; of driving gearing therefor comprising a separable gear box closing the driving end 40 of the magneto, a gear in the gear box, a shaft fast with the gear and extending through and beyond the gear box, a bearing for the shaft carried by one member of the 45 gear box and closed to the interior of the magneto, a second bearing for the shaft carried by the other member of the gear box, a driving handle fast on the exteriorly projecting end of the shaft, and a pinion 50 mounted in the gear box on the end of the armature shaft in engagement with the gear, the gear box member adjacent the magneto having a bearing for the armature shaft and a cup-shaped portion enclosing the slip ring. 55

7. The combination of a starting magneto having an armature with a slip ring, driving gearing for said armature and ring, and means for operating said gearing, and a housing for said gearing, said housing having 60 bearings for said gearing and armature and having an extension around said slip ring.

In testimony whereof I affix my signature.

WOLFGANG ERNEST SCHWARZMANN.
